US0D1111813S

(12) United States Design Patent (10) Patent No.: US D1,111,813 S
 Marushko et al. (45) Date of Patent:  Feb. 10, 2026

(54) FOOD BAR PACKAGING(71) Applicant: Intercontinental Great Brands LLC,
East Hanover, NJ (US)(72) Inventors: Alexandra Marushko, East Hanover,
NJ (US); Valerie Van Arkel, East
Hanover, NJ (US); Jennifer
Zeremenko, East Hanover, NJ (US);
Stephen Patrick Fisher, Albertville,
MN (US); Sarah Hefetz, Forest Hills,
NY (US)(73) Assignee: Intercontinental Great Brands LLC,
East Hanover, NJ (US)() Term: 15 Years(21) Appl. No.: 29/988,675(22) Filed: Feb. 5, 2025(51) LOC (15) Cl. 09-01

(52) U.S. Cl.

USPC D9/643; D9/434

(58) Field of Classification Search

USPC D9/414, 430, 432, 434, 643; D20/23, 29

CPC B65D 2203/02

See application file for complete search history.

(57) CLAIM

The ornamental design for food bar packaging as shown and described.

DESCRIPTION

The sole FIGURE is a front view of food bar packaging, showing our new design.

The dashed lines show portions of the food bar packaging that form no part of the claimed design. The dash-dot-dash lines show boundaries of the claimed design and form no part of the claimed design.
